UNITED STATES PATENT OFFICE.

CHARLES C. SPREEN, OF DETROIT, MICHIGAN, ASSIGNOR TO ELECTRIC REFRIGERATION CORPORATION, OF DETROIT, MICHIGAN, A CORPORATION OF MICHIGAN.

MECHANICAL REFRIGERATION.

Application filed January 10, 1927. Serial No. 160,293.

My invention relates to mechanical refrigeration and particularly to means for supporting the expander of a mechanical refrigeration system in spaced relation to the walls of the refrigerating compartment, and the principal object of my invention is to provide new and improved means of this type. In the drawings accompanying this specification and forming a part of this application I have shown, for purposes of illustration, one form which my invention may assume, and in these drawings:

Figure 1 is a fragmentary elevation showing my invention applied to a refrigerator cabinet, while

Figure 2 is a section on the line 2—2 of Figure 1.

The embodiment of my invention shown herein comprises a refrigerator cabinet 11 having a refrigerating compartment 12 accessible through a door opening 14 and containing an expander 13 supported in spaced relation to the walls of the compartment 12.

The support for the brine tank comprises 25 pairs of bars 15 and 16 attached at spaced points to opposite sides of the door opening 14 and having their free ends convergingly projecting into the compartment 12 with the free ends of like members of each 30 pair of bars connected to a cradle member 17.

The free ends of the bars 15 and 16 are provided with a series of spaced apertures 18 while the cradle members 17 have similar apertures 19 in their ends. By this arrangement connecting bolts 30 may be passed through selected pairs of apertures 18 and 19 thereby adapting the support to compartments and expanders of different size.

40 In assembling the support the bars are first movably attached to the sides of the door opening 14 by screws 20, or the like, and after the cradles 17 are adjusted to fit the compartment additional screws 21 are 45 inserted thereby fixedly attaching the bars 15 and 16 in adjusted position.

From the above disclosure it will be obvious to those skilled in the art that I have provided new and improved means, adjustable to fit compartments and expanders of different size, for supporting an expander in a compartment of a refrigerator cabinet.

It will also be obvious to those skilled in the art that the embodiment of my inven-

tion herein shown and described may be variously changed and modified without departing from the spirit of my invention or sacrificing the advantages thereof, and it therefore will be understood that the disclosure herein is illustrative only, and that my invention is not limited thereto.

I claim:

1. In a mechanical refrigerator, comprising a refrigerator cabinet provided with a compartment, with an opening affording access to said compartment, and with a door for closing said opening: means for supporting an expander within the compartment, comprising a plurality of cradles supporting said expander, and means connecting each cradle to the cabinet adjacent opposite sides of said opening.

2. In a mechanical refrigerator, comprising a refrigerator cabinet provided with a compartment, with an opening affording access to said compartment, and with a door for closing said opening: means for supporting an expander within the compartment, comprising a plurality of cradles supporting said expander and bars connecting each cradle to the cabinet adjacent opposite sides of said opening.

3. In a mechanical refrigerator, comprising a refrigerator cabinet provided with a compartment, with an opening affording access to said compartment, and with a door for closing said opening: means for supporting an expander within the compartment, comprising a plurality of cradles supporting said expander, and supporting means for connecting each cradle to the cabinet adjacent opposite sides of said opening, and having said cradles and said supporting means formed for connecting to each other respectively at any one of a plurality of points.

4. In a mechanical refrigerator, comprising a refrigerator cabinet provided with a compartment, with an opening affording access to said compartment, and with a door for closing said opening: means for supporting an expander within the compartment, comprising a plurality of cradles supporting said expander, and having a plurality of spaced apertures, pairs of bars having one end attached to the walls of said opening and a plurality of spaced apertures at their free ends, and means engaging se-

lected ones of the apertures in said cradles and said bars for attaching said cradles to said bars, selectively.

5. In a mechanical refrigerator, comprising a refrigerator cabinet provided with a compartment, with an opening affording access to said compartment, and with a door for closing said opening; means for supporting an expander within the compartment, comprising a plurality of cradles sup-

porting said expander, and bars for connecting each cradle to the cabinet adjacent opposite sides of said opening, and having said cradles and said bars formed for connection to each other at any one of a plurality of points respectively. 15

In testimony whereof I hereunto affix my signature.

CHARLES C. SPREEN.
